Primary Examiner — Mitchell Siegel(74) *Attorney, Agent, or Firm* — Lapple Ubell IP Law, LLP; Matthew C. Lapple(57) **CLAIM**

The ornamental design for a wading pool, as shown and described.

DESCRIPTION

FIG. 1 is a front perspective view of a wading pool in accordance with the present invention;

FIG. 2 is a top view thereof;

FIG. 3 is a side view thereof along the long axis of the pool; and,

FIG. 4 is a side view thereof along the short axis of the pool. The bottom view of the pool is not claimed. In the figures, portions shown in broken lines do not form a part of the claimed invention.
